INVENTOR

BY *Victor J. Evans*

ATTORNEY

UNITED STATES PATENT OFFICE.

MERLE L. NEDDS, OF SANDPOINT, IDAHO.

GAME.

Application filed July 2, 1926. Serial No. 120,159.

This invention relates to a game, the general object of the invention being to provide a game which will not only afford amusement to those playing it but will also act to instruct the players on matters relating to the United States, such as the various States, their capitals, principal cities of the States and the railroad lines passing through the States.

Another object of the invention is to provide a map of the United States, with the railroad routes thereon, which includes the various stations along the routes, with tickets for the various routes, one of which is to be drawn by each player to indicate which route he is to travel, with numbers on the map adjacent the stations and similar numbers on the ticket or another part of the game associated with instructions for indicating what the player is to do when he reaches the stations with these numerals thereon.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:

Figure 1 is a view of a board having the map of the United States thereon, with the various railroad routes.

Figure 2 is a view of one of the tickets which forms part of the game.

Figure 3 is a view of the dice which also forms part of the game.

As shown in Figure 1, the game comprises a map of the United States which has thereon the lines 10 representing various railroad routes and each line has the dots 11 thereon for representing the stations along the route, with the printed name of the station opposite the dot. Some of the stations or all of the stations may be marked with numerals, such as shown at 12.

The game also includes ticket strips, such as shown at 13 in Figure 2, these strips giving the names of the various routes and the names of the stations. I prefer to place on

each ticket the name of the various railroads over which one must travel in passing over the entire route. Such names are shown at 14 in Figure 2. The ticket is also provided with the numerals 12' which are the same as those shown at 12 on the map and opposite each numeral 12' are printed instructions 15 for telling what the player must do when he reaches a station numbered the same as the number opposite a certain instruction.

I prefer to play the game with the use of dice, such as shown at 16 in Figure 3, though it may be played with a spinner of known construction.

Each player draws a ticket strip from a pile of these strips and he must follow the route indicated by the strip which he has drawn. For instance, the player drawing the ticket shown in Figure 2, must travel over the route starting from San Francisco and ending at Washington and passing over the northern part of the map. Each player rolls the dice in turn and he moves the same number of stations as the number uppermost on the dice. For instance, if the numeral 3 is turned up, he would move his player piece to the third station on the map of the route from San Francisco to Washington, which is "Salem, Oregon". He then notes the numeral opposite the station, which in this case would be "7" and he then refers to the number 7 on the ticket, which instructs him to miss his turn or throw, for the reason that he has missed connections and must wait over. Each of the other players then throws, but the first player must wait two throws of the other players as he has missed his play. If a player reaches a station marked with the numeral 1, he can again throw the dice, for the reason that his train connections are good. Thus the player is advanced or retarded according to the instructions on the ticket slip and the player reaching the end of the route first wins the game.

It will, of course, be understood that the instructions may be placed on other parts of the game other than the ticket and they need not be the same, as shown in Figure 2, as other reasons for advancing or retarding the progress of the player could be used. It may be that two players will travel over the same route, and when this occurs and a

player reaches a station marked with the numeral 8, the other player cannot pass him until he moves from this station.

I prefer to give the game the title of "The Game of Via".

It is though from the foregoing description that the advantages and novel features of my invention will be readily apparent.

I desire it to be understood that I may 10 make changes in the construction and in the combination and arrangement of the several parts, provided that such changes fall within the scope of the appended claims.

What I claim is:—

- 15 1. A game of the class described comprising a board having a map thereon with railroad routes marked on the map, with the stations along the route, ticket strips for the various routes which are to be drawn by 20 the players to indicate which route each player is to take, each strip having thereon the names of the stations along the route and the names of the railroads used in traveling over the routes, means for indicating 25 the number of stations to be moved at each

play, the stations on the map being provided with characters and a portion of the ticket having similar characters thereon with instructions opposite each character for indicating how the player is to be advanced or retarded.

2. A game of the class described comprising a board having a map thereon with railroad routes marked on the map, with the stations along the route, ticket strips for the various routes which are to be drawn by the players to indicate which route each player is to take, each strip having thereon the names of the stations along the route and the names of the railroads used in traveling over the routes, means for indicating the number of stations to be moved at each play, the stations on the map being provided with characters and the ticket having similar characters thereon with instructions opposite each character for indicating how the player is to be advanced or retarded.

In testimony whereof I affix my signature.

MERLE L. NEDDS.
